UNITED STATES PATENT OFFICE.

WILLIAM A. HALL, OF BROOKLYN, NEW YORK.

ENGINE-BOX.

1,180,033.

Specification of Letters Patent. Patented Apr. 18, 1916.

Application filed January 14, 1916. Serial No. 72,166.

To all whom it may concern:

Be it known that I, WILLIAM A. HALL, a citizen of the United States, and a resident of the borough of Brooklyn, in the county of Kings and State of New York, have invented certain new and useful Improvements in Engine-Boxes, of which the following is a specification.

This invention relates to improvements in engine boxes.

In particular the invention relates to improvements in the boxes, or cases, which inclose the engines of motor boats, although the invention is not limited to use with such engines.

The purpose of the invention is to provide an engine box of such shape and construction that it will give convenient access to the engine, and especially to the fly-wheel or cranking mechanism of gasoline engines, so that the person in charge of the engine can readily start it and attend to it as necessary. In the boxes, as heretofore designed and constructed, it has been impossible for the attendant or engineer to reach the fly-wheel in an easy and natural position because of the height of the box. He has to practically get off his feet in order to bend over the high front end of the box and reach down to the fly-wheel to start his engine. The purpose of the present invention particularly is to obviate this serious inconvenience. In accomplishing this, I form the box with that end which is nearest to the fly-wheel, and over which the attendant must reach, in such a form as renders that end of the box low enough to give convenient access to the motor while the main part of the box is as high as is required. A cover, which can be easily opened and closed by the attendant, is provided at this part of the box, so that whenever desired the box can be closed to protect the engine from spray, etc., and yet can be easily and conveniently opened by the attendant. I also provide a conveniently operated cover at the other end of the box to give access to that part of the engine whenever necessary.

It is another purpose of the invention to provide a cheap and easily constructed box.

Referring to the drawings which accompany the specification to aid the description, Figure 1 is a diagrammatical plan view of a motor boat with my improved box. Fig. 2 is a side elevation of the box and showing the covers. Fig. 3 is a plan

view of the box with the covers. Fig. 4 is a broken detail about on the plane of the line 4-4 of Fig. 3, and showing the preferred construction of the cover and its guides. Fig. 5 is a broken detail on the plane perpendicular to Fig. 4, and illustrating the preferred construction for attaining the proper slope of the top of the box.

A being the motor boat provided with a gasoline engine, and B being the box, said box is constructed in the following manner: Any suitable material may be employed, but I prefer to construct the box of sheet metal with suitable stiffening angle-iron frames. Said box is of substantially rectangular shape in plan, and is so formed that that end of the box which is adjacent to the fly-wheel is shaped at the top on an inclination as seen in Fig. 2, so that the front end of the box, or that end adjacent to the fly-wheel, is lower than the main body of the box, and so low that the attendant can readily reach down over that end to grasp the fly-wheel and start the engine. The top of the box at said front end is open and is provided with a sliding cover D, which is provided with bent parallel edges d-d sliding on guides e, which guides are arranged at the top of the box at the proper inclination. Said guides e-e may be secured to the box in any suitable manner; but for cheapness of construction and in order that common angle-irons may be used, I prefer the construction illustrated in Fig. 5; wherein wedged shaped blocks f are employed to give the proper angle to the angle-irons g, said blocks f and angle-irons g being riveted to the sides b of said box. An other angle-iron h is then riveted or bolted above said angle-iron g, the bent edge of the side plate b being secured between said angles h and g as seen in Fig. 5. Finally an angle e is secured to said angle h, and will be at the proper inclination to form the guide for one side of the cover, the other side of the box being provided with a similar construction. Thus the cover slides forward and back on its guides, being provided with suitable handles k-k to assist in readily moving it to and fro. The rear end of the box is provided at the top with a similar cover L, except that said cover L is arranged horizontally as indicated. The bottom of said box B is preferably open at the bottom and flanges are provided for secur-

ing said box firmly to the floor or other part of the boat.

From the foregoing description, it will be apparent that a box such as above described has its end adjacent to the fly-wheel so low that the attendant can readily reach over it to grasp and operate the fly-wheel in starting the engine; and in practice this is found to be a very important feature in the construction of the engine boxes in motor boats, and especially when the boat is in a hard sea way, when the motion of the boat renders it very difficult, under the present construction of the boxes, for the engine attendant to hold his footing in order to start his engine should it accidentally stop. This invention therefore greatly increases the convenience of the operation of operating the engine and the safety of the motor

boat in circumstances which would otherwise be full of peril.

Now having described my improvements I claim as my invention.

In a box for explosive engines, the combination with the downwardly inclined top of the box of beveled blocks and angle-irons adapted to form cover guides at an inclination corresponding to the inclination of the top of the box, and a sliding cover working on said guides, substantially as described.

Signed at borough of Brooklyn, in the county of Kings, and State of New York, this 12th day of January, A. D. 1916.

WILLIAM A. HALL.
